UNITED STATES PATENT OFFICE.

JOHN PATRICK FERRITER, OF JACKSONVILLE, FLORIDA, ASSIGNOR OF ONE-HALF TO
THOMAS J. PETERS, OF PETERS, FLORIDA.

TELEPHONE TALKING-COIL AND CIRCUIT CONNECTIONS.

1,234,651.

Specification of Letters Patent. Patented July 24, 1917.

Application filed September 20, 1916. Serial No. 121,143.

To all whom it may concern:

Be it known that I, JOHN P. FERRITER, a citizen of the United States, and a resident of Jacksonville, in the county of Duval and 5 State of Florida, have invented a new and Improved Telephone Talking-Coil and Circuit Connections, of which the following is a full, clear, and exact description.

This invention relates to telephony, and 10 deals particularly with an improved talking coil and circuit connections therefor.

The object of the invention is to produce a simple, novel and efficient talking coil which produces a greater amplitude of variation in the current induced in the talking coil secondary winding when the transmitter is in operation than can be produced with an ordinary talking coil and ordinary connections, the current flow being the same in 20 both cases.

In carrying out the invention, the talking coil has two primary windings consisting of a twisted pair of wires wound around an iron core, which may be open or closed, and 25 a secondary winding of one wire wound over the primaries. An opposite end of each primary winding is connected to the same pole of a battery. The other end of one primary winding is connected to the opposite 30 pole of the battery through one winding of a one to one transformer and a resistance in series with it, which resistance is equal to the resistance of the transmitter when the transmitter is at rest. The second end of 35 the other primary winding is connected to the same battery terminal through the second winding of the transformer and the transmitter, in series.

For a more complete understanding of the 40 invention reference is to be had to the following description and claims taken in connection with the accompanying drawing, which illustrates certain embodiments of the invention and wherein similar characters of 45 reference indicate corresponding parts in both the views, in which—

Figure 1 is a diagrammatic view of the telephone talking coil and circuit connections with a carbon transmitter or any other 50 equivalent type, whose actions depends upon the variation of resistance between the electrodes; and

Fig. 2 is a similar view showing a condenser transmitter and a balancing condenser in the two branches of the primary 55 circuit.

Referring to the drawing, A designates a talking coil which has two primary windings p^1 and p^2 , one being shown by a heavier line than the other for the sake of clearness. 60 These windings surround an open or closed circuit iron core c , represented by dotted lines, and surrounding the primary windings is a secondary winding s , which is connected in the usual manner with a telephone 65 line, but in the drawing the secondary winding is shown to one side of the primary windings. The primary windings comprise a twisted pair of wires, and one end of one winding and the opposite end of the other 70 are connected by a wire 1 with one pole or terminal of a battery or other source of continuous current B. The other terminals of the primary windings are connected respectively with the wires 2 and 3, which 75 are connected by a common wire 4 with the opposite pole or terminal of the battery B. Included in the wires 2 and 3 are transformer windings t^1 , t^2 , wound around an annular core 5 and having a transforming relation of one to one. In the wire 3 is an ordinary carbon transmitter 6, and in the opposite side of the circuit or the wire 2 is a non-inductive resistance 7, equal to the normal 80 resistance of the transmitter 6. 85

In the circuit connection shown in Fig. 2 a condenser transmitter 6^a is shown in one branch of the primary circuit, and this is balanced by a condenser 7^a of the same normal capacity as the condenser 6^a. The action is substantially the same as in the first arrangement. 90

The operation is as follows:

When the transmitter is at rest, a current passes from the battery through the primary 95 windings in opposite directions and sets up no magnetic action in the core. This is due to the primaries consisting of a twisted pair, which places both wires in exactly the same relation to the core, no matter how they are 100 wound. This absence of magnetic effect when the transmitter is at rest precludes the possibility of magnetic saturation of the core, which is a serious fault inherent in ordinary talking coils and which conduces to 105 sluggishness of action. This sluggishness of action aids in producing side tones in the receiver and also contributes to the distortion of the electrical waves produced by the action of the transmitter, the result being 110 defective articulation in the received signals. I do not claim that this is the only cause of

defective articulation, but that it is a contributing cause.

When the transmitter is actuated, by the voice or otherwise, the consequent change in 5 the transmitter resistance destroys the resistance balance of the Wheatstone bridge arrangement of which it is a part and allows of a preponderance of current passing through one of the primary windings of the 10 talking coil, which one depending upon whether the transmitter has more or less resistance than the resistance coil in the opposite arm of the bridge. It will be seen readily that, although this action does not 15 set up true alternating currents in the talking coil primaries, it does actually set up alternations in the magnetic lines of force in the core. It could not be otherwise, because, when the transmitter is at rest, there 20 are no magnetic lines of force in the core, while, when the transmitter is in action, the lines of force must necessarily be set up in correspondence with the transmitter variation from a subnormal to a supranormal 25 resistance.

This action of the coil is a great advantage over other types of coil, but it does not increase the amplitude of current produced in the secondary winding; it only quickens the 30 action by relieving the core of magnetic saturation.

The object of placing a transformer in the circuit is to double the effect in the talking coil secondary of any inequality of potential applied to one or the other of the 35 primaries. This is done in the following manner:

A preponderance of current produced by 40 the action of the transmitter, which, in a talking current, is always a momentary impulse, in passing through one arm of the bridge, necessarily passes through one winding of the transformer. This impulse induces a corresponding impulse in the opposite winding of the transformer and in the 45 opposite direction. The strength of this induced impulse will be practically the same as that of the impulse inducing it and it will oppose the current passing through the bridge arm opposite to the arm carrying the 50 original impulse. This opposition will, in effect, double the magnetic effect in the core produced by the original impulse and cause a current to pass through the secondary 55 winding which will have twice the amperage that can be produced in an ordinary coil, using the same transmitter with the same amount of current passing through the transmitter. The action of this arrangement 60 can be shown to be exactly as described. If the terminals of one transformer winding be reversed, thus inducing an im-

pulse in the wrong direction, the result will be that the original impulse is exactly neutralized and no sound is produced in a receiver placed in series with the talking coil secondary. 65

From the foregoing description, taken in connection with the accompanying drawing, the advantages of the construction and 70 method of operation will be readily understood by those skilled in the art to which the invention appertains, and while I have described the principle of operation, together with the device which I now consider to be 75 the best embodiment thereof, I desire to have it understood that the device shown is merely illustrative and that such changes may be made when desired as fall within the scope of the appended claims. 80

Having thus described my invention, I claim as new and desire to secure by Letters Patent:

1. A telephone talking coil comprising a pair of primary windings composed of two 85 twisted wires helically wound, a core within the windings, and a secondary winding consisting of a single wire wound around the primary windings.

2. A telephone talking coil comprising a 90 pair of primary windings composed of two twisted wires helically wound, a core within the windings, a secondary winding consisting of a single wire wound around the primary windings, a source of current 95 having one terminal connected with the right end of one of the primary windings and the left end of the other primary winding, wires connected with the other ends of the primary windings and with the opposite 100 terminal of the source of current, a one to one transformer connecting the wires inductively together, a telephone transmitter in one of the wires, and an electrical device in the other wire having an electrical value 105 equal to the normal value of the transmitter.

3. In a telephone system, the combination of a talking coil comprising primary windings composed of a twisted pair of wires helically wound, and a secondary winding 110 inductively related thereto, a source of current connected with the right end of one primary winding and the left end of the other primary winding, a wire connected with the free end of one of the primary 115 windings and also with the said source of current, a wire connected with the free end of the other primary winding and also connected with the source of current, a transmitter in one of the wires, and means in the 120 other wire for normally balancing the transmitter.

JOHN PATRICK FERRITER.
